UNITED STATES PATENT OFFICE.

OLIVER B. WOODROW, OF NEWTON, IOWA.

DRIVING MECHANISM.

No. 921,195.

Specification of Letters Patent.

Patented May 11, 1909.

Application filed March 13, 1908. Serial No. 420,954.

To all whom it may concern:

Be it known that I, OLIVER B. WOODROW, a citizen of the United States, residing at Newton, in the county of Jasper and State of 5 Iowa, have invented a new and useful Driving Mechanism, of which the following is a specification.

The object of my invention is to provide means of simple, durable and inexpensive 10 construction, permanently connected to the frame of a washing machine, whereby all of the operating mechanism, including an electric motor or other suitable power device, may be mounted beneath the body of a 15 washing machine in such a manner as to balance the weight of the washing machine, and to be contained within the same amount of floor space as the washing machine of itself would occupy, and further, to provide operating means of this kind whereby the operator 20 may readily and easily control the movement of either the washing machine or wringer, so that either may be stopped or started instantly, whenever desired, and so 25 that either the wringer or washing machine may be operated or both thrown out of gear, but only one at a time may be operated.

My invention consists in the construction, arrangement and combination of the various 30 parts of the device, whereby the objects contemplated are attained, as hereinafter more fully set forth, pointed out in my claims and illustrated in the accompanying drawings, in which—

35 Figure 1 shows a side elevation of the complete device embodying my invention. Fig. 2 shows a detail plan view illustrating the means for operating the agitator shaft. Fig. 3 shows a rear end elevation of the entire 40 device embodying my invention. Fig. 4 shows an enlarged detail sectional view of the clutch device, and—Fig. 5 shows a detail view of the lower end of the lever for operating the movable sleeve of the clutch device. 45

Referring to the accompanying drawings, I have used the reference numeral 10 to indicate the washing machine body supported upon the legs 11. Mounted in the cover of 50 the body is an agitator shaft 12, provided with a pinion 13.

At the front of the washing machine body is a bracket 14, to which an operating lever 15 is fulcrumed. This operating lever has 55 pivoted to its top a rack bar 16 in mesh with

the pinion 13, and pivoted to the lower end of the lever 15 is a pitman 17.

Mounted at the rear of the washing machine body on the cover thereof, is a wringer support 18, to which a wringer 19 of ordinary construction is attached. This wringer is provided with a grooved pulley 20 attached to one of the roller shafts.

Mounted beneath the body 10, and between the supporting legs 11, is a platform 21, and supported upon this platform is an electric motor 22, or other suitable power device. Fixed to the shaft of the motor 22 is a small pulley 23.

Mounted in bearings 24 below the body 10, 70 is a shaft 25 having fixed to one end thereof a large pulley 26, which pulley is connected by means of the belt 27 with the small pulley 23 on the motor. Rotatably mounted upon the shaft 25 is a small pinion 28 having a 75 ratchet clutch member 29 connected therewith. Fixed to the other end of the shaft 25 is a sleeve 30 having thereon a small pulley 31 connected by a belt 32 with the pulley 20. Said sleeve is also provided with 80 a ratchet clutch member 33. Slidably mounted upon the shaft 25 between said clutch members 29 and 33, is a sleeve 34 having an annular groove 35 formed thereon. This sleeve is provided with a longitudinal 85 slot 36, and a screw 37 is passed through said slot and seated in the shaft 25, to thereby permit the sleeve to move longitudinally upon the shaft, and to prevent its rotation thereon. On one end of the sleeve 34 is a 90 ratchet clutch member 38, to co-act with the clutch member 29, and on its other end is a ratchet clutch member 39 to co-act with the clutch member 33.

Mounted beneath the body 10 is a lever 40 95 having a fork 41 at its lower end to enter the groove 35. This lever has a pitman 42 pivoted to its central portion, the outer end of the pitman being pivoted to a lever 43, which lever is fulcrumed to the bracket 44, 100 and is provided at its upper end with a lug 45 designed to enter the notches 46 in the curved bracket 47, said lug being yieldingly held in one of the notches 46 in which it may be placed, by the resiliency of the lever 43. 105 The arrangement of these parts is such that when the lever 43 is in the position shown in Fig. 3, then the sleeve 34 is held midway between the ratchet members 29 and 33, and when the lever 43 is moved to one 110

side of its central position, the clutches 38 and 29 will engage, and when moved to its other limit, the clutches 39 and 33 will engage.

5 Mounted beneath the machine body is a large pinion 48 having the pitman 17 pivoted to it, and arranged in mesh with the small pinion 28, so that when said small pinion is rotated, the rack bar 16 will be 10 reciprocated and an alternating rotary motion will be imparted to the agitator shaft.

In practical operation, and assuming that the motor is running, and assuming further that the sleeve 34 is in its central position, 15 then neither the agitator nor the wringer are being operated. If it is desired to operate the agitator, then the operator grasps the lever 43 and moves its upper end away from the body 10, thus throwing the 20 clutch members 28 and 29 into engagement. This will cause the small pinion 28 to be rotated with the shaft 25, and thereby operate the large pinion 48, the pitman 17, the lever 15, the rack bar 16, and the pinion 25 13 on the agitator shaft. If it is desired to stop the movement of the agitator, the lever 43 is returned to its central position, and if it is desired to operate the wringer, the upper end of the lever 43 is moved toward 30 the body 10, thus throwing the clutch members 33 and 39 into engagement.

In a device of this kind, and especially in connection with the operation of a wringer, it is desirable to provide means whereby 35 the operating devices may be instantly stopped. For instance, in regard to the wringer, and in the event that an article of clothing is being run through the wringer, and the article should become wound upon 40 the rollers, or should become entangled with other articles, then if the motion of the wringer was continued, either the article or the wringer might become damaged, and if, in order to stop the wringer it was necessary 45 to stop the motor and all the other machinery, then in many cases this could not be accomplished quickly enough to prevent damage. However, by means of my invention, either the wringer or the agitator may 50 be thrown out of gear instantly, whenever the occasion demands, and on account of the friction which both the wringer and the agitator are subjected to, they will instantly stop whenever the clutch device is moved 55 to position for throwing them out of gear.

Having thus described my invention, what I claim and desire to secure by Letters Patent, is—

1. In a gearing device of the class described, the combination of a frame, supporting legs for the frame, a platform secured to the supporting legs below the frame, a shaft at the top of the frame, a motor mounted on the said platform, an operating device connected with the motor, and with the said

shaft for imparting an alternating rotary motion to the shaft, a controlling lever, and means actuated by the controlling lever for throwing the operating device into or out of operative connection with the motor. 70

2. In a gearing device of the class described, the combination of a frame, supporting legs for the frame, a platform fixed to the supporting legs below the frame, a motor on the platform, a shaft-mounted in the top of the frame, a device mounted on top of the frame, an operating device connected with the motor and with the said shaft for imparting an alternating rotary motion to the latter, an operating device connected with the motor and with the said device for operating the latter, a controlling lever and means operated by the controlling lever for throwing either of said operating devices into or out of operative connection with the motor. 75 80 85

3. In a gearing device of the class described, the combination of a frame, supporting legs therefor, a platform beneath the frame fixed to the supporting legs, a motor thereon, a rotatable shaft, means for rotating the shaft by power from the motor, a small pinion and a small pulley rotatably mounted on said shaft, and each having a clutch member, a sliding clutch member mounted on the shaft and capable of engaging either of said clutch members, or of standing in position out of engagement with both, a controlling lever for operating said sliding clutch member, a shaft at the top of the frame, means for operating said shaft by power from the small pinion, a device on top of the frame, and means for operating the same by power from the small pulley. 90 95 100

4. In a gearing device of the class described, the combination of a frame, supporting legs therefor, a platform beneath the frame fixed to the supporting legs, a motor thereon, a rotatable shaft, means for rotating the shaft by power from the motor, a small pinion and a small pulley rotatably mounted on said shaft, and each having a clutch member, a sliding clutch member mounted on the shaft and capable of engaging either of said clutch members or of standing in position out of engagement with both, a controlling lever for operating said sliding clutch member, a shaft at the top of the frame, means for operating said shaft by power from the small pinion, a device on top of the frame, means for operating the same by power from the small pulley, and means for supporting the controlling lever in position with the sliding clutch member out of engagement with both of the other clutch members, or in engagement with either. 105 110 115 120 125

5. A gearing device of the class described, comprising a frame, supporting legs therefor, a platform secured to the supporting legs below the frame, a motor mounted on said platform, a rotatable shaft mounted beneath 130

the frame, means for operating said shaft from the motor, a small pinion rotatably mounted on the shaft and having a clutch member, a small pulley rotatably mounted 5 on the shaft, and having a clutch member, a sliding clutch member mounted on the shaft and capable of standing in position out of engagement with both of the other clutch members or in engagement with either, a lever 10 fulcrumed to the bottom of the frame for controlling the sliding clutch member, a pitman connected with said lever, a controlling lever fulcrumed to the side of the frame and having a lug near its upper end, a notched 15 bracket fixed to the frame, to be engaged by said lug, a shaft mounted in the top of the

frame, a pinion thereon, a rack in engagement with said pinion, a lever fulcrumed to one side of the frame and pivoted to said rack, a pitman pivoted to the lower end of said 20 lever, a large pinion mounted beneath the frame and in mesh with said small pinion and having said pitman pivoted to it, a device on top of the frame, a pulley on said device and a belt for connecting said pulley with the said 25 small pulley, for the purposes stated.
